UNITED STATES PATENT OFFICE

120,144

DESIGN FOR AN ADVERTISING DEVICE

Leo T. Siddall, Kansas City, Kans.

Application February 5, 1940, Serial No. 90,021

Term of patent 7 years

To all whom it may concern:

Be it known that I, Leo T. Siddall, a citizen of the United States, residing at Kansas City, in the county of Wyandotte and State of Kansas, have invented a new, original, and ornamental Design for an Advertising Device, of which the following is a specification, reference being had to the accompanying drawing, forming a part thereof.

Fig. 1 is a side elevational view of the advertising device, showing my design.

Fig. 2 is a plan view thereof.

Fig. 3 is a front end elevational view thereof.

I claim:

The ornamental design for an advertising device, as shown.

LEO T. SIDDALL.
